PRECISION STRESS BREAKER FOR REMOVABLE PARTIAL RESTORATIONS

Placido G. Baca and Faustine G. Baca,
Los Angeles, Calif.

Application April 27, 1950, Serial No. 158,442

13 Claims. (Cl. 32—7)

1

Our invention relates generally to the dental art, and particularly to improvements in partial dentures. Specifically, the invention pertains to an improved connecting means, commonly referred to as a stress-breaker, by which a partial dental plate is connected to a natural abutment tooth in a manner such that movement of the partial plate, relative to the abutment tooth, is permitted so as to avoid objectionable stress or pressure on the abutment tooth during mastication.

It is well recognized in the dental art that partial dentures or restorations which replace less than all the natural teeth of a jaw have several disadvantages which are not readily overcome. For example, it is necessary that such a partial denture be suitably anchored or detachably connected to a natural abutment tooth which is disposed immediately forward of that portion of the gum to which the partial plate is to be applied. It has been determined in the past that when such a plate is rigidly connected at one end to an abutment tooth by means of a clasp which is carried by the plate and which at least partially encircles the abutment tooth, the plate is, in effect, a cantilever which rests against the relatively soft gum tissue. For this reason, it is well known that during mastication the partial denture is forced in a direction toward the gum and this results not only in flexing of the plate and its clasp but imposes considerable strain on the abutment tooth which, over a period of time, may become loose in its jaw socket. In many such cases, the loosened abutment tooth becomes useless as an anchor for the partial denture and as a means of mastication and its extraction is necessitated, at which time the next anterior tooth is utilized as an abutment for a new partial denture or restoration which must now include a tooth to replace the extracted one.

Many expedients have been proposed for obviating the difficulty discussed above, it being common practice to provide a so-called "stress-breaker" device for connecting a partial denture to a natural abutment tooth in such a way that relative movement between the denture and the abutment tooth is permitted so as to relieve the strain which would otherwise be imposed on the abutment tooth during mastication. Many forms of stress-breakers have been proposed for accomplishing the desired result, such devices usually including a socket member carried by the partial denture, and a support member detachably connected to the abutment tooth by means of an integral clasp, and having an end disposed in the socket member. By this construction,

vertical sliding movement of the socket member with respect to the relatively stationary support member is permitted when the partial denture is pressed against the soft gum tissue during mastication so that strain on the abutment tooth is minimized. The result is also attained by providing a stress-breaker connection which embodies a socket member on the partial denture and a ball or other similar element detachably connected to the abutment tooth and adapted to swivel within the socket member, this construction resulting in a pivotal action of the denture with respect to the abutment tooth. In still another form of stress-breaker, the relatively stationary element is so connected to the socket member that a combined vertical sliding movement and pivotal action is effected.

Such prior stress-breaker devices are subject to various disadvantages. In the first place, when the device is constructed to allow only straight vertical movement, the delicate components thereof are themselves subjected to considerable stress, this being due largely to a bending moment imposed against these parts, particularly when food is masticated at the posterior end of the partial denture. As might be expected, distortion of the stress-breaker components results in a loose connection which is very objectionable. When a stress-breaker device of the pivotal type is employed, the posterior or distal end of the partial denture may have unrestricted, substantially vertical, movement while the range of vertical movement at the anterior end of the denture is very limited so that strain may be imposed upon the abutment tooth. Such a pivotal connection also allows transverse rocking motion of the partial denture and this is highly objectionable. A stress-breaker device operating upon the combined vertical and pivotal movement principle has been considered more practical but such a device is subject to the same disadvantages, to a lesser degree.

It frequently occurs that a partial denture is applied to use at each side of a jaw and in such cases the dentures are connected by a curved lingual bar which is connected to and extends between the anterior ends of the dentures at the rearward side of the frontal portion of the gum and the natural teeth thereof. The lingual bar is intended to rest lightly against the gum and it is imperative that pressure of the bar or sliding movement thereof against the gum be prevented if irritation of the gum is to be avoided. It has been found that such impingement of the lingual bar cannot be overcome by the use of any of the stress-breaker devices

discussed above for the reason that the vertical or pivotal movement, or both, imparted to either partial denture during mastication is communicated directly to the lingual bar to cause the latter to press into a rub along the gum, and this results in considerable discomfort to the wearer.

It is a primary object of our invention to obviate the deficiencies of prior dental stress-breaker devices discussed above by providing a stress-breaker which effects movement of a partial denture in a path which extends obliquely in a posterior direction with respect to the abutment tooth to which the denture is anchored. By this provision, the partial denture is caused to bear against the gum tissue with uniform pressure throughout its length so as to provide greater comfort for the wearer. Moreover, since the movement of the partial denture is restricted to such an oblique path, true pivotal movement thereof is prevented so that impingement of the anterior end of the denture against the abutment tooth and the gum tissue surrounding the same is effectively avoided. Furthermore, since the denture moves away from the horizontal plane of the teeth of the jaw and posteriorly during mastication, it follows that a lingual bar connected thereto must also move in a like path to cause it to substantially follow the contour or profile of the gum to prevent impingement or rubbing of the lingual bar against the gum, this highly desirable result being attained when either or both dentures of a pair of dentures located at either side of the jaw are utilized during the mastication process.

Another object of the invention is to provide a dental stress-breaker which is very simple in construction, the device comprising a slide member of channel shape suitably joined to the anterior end of the partial denture and a support bar of rectangular cross section having an integral clasp portion by which the bar is detachably connected to the abutment tooth and provided with an elongate opening extending in a direction away from the horizontal plane of the teeth of the jaw and posteriorly with respect to the abutment tooth, said support bar being receivable in the slide member, the device further including a connecting means, consisting of a screw, pin or the like, carried by and extending between the side walls of the slide member and through said elongate opening. By this construction, the partial denture is connected to the abutment tooth and movable with respect thereto in a path extending away from the horizontal plane of the teeth of the jaw and posteriorly of the abutment tooth for the purpose previously explained. A related object is to provide a stress-breaker device in which the slide member is carried by the saddle of the denture and is embedded in the material of the partial denture. Another object is to provide a device of this character in which the connecting means consists of a screw having a shank passing through an aperture in the inner side wall of the slide member and through the elongate opening of the support bar member, said screw having a threaded end screwed into a threaded hole in the outer side wall. By this means, the connecting screw is inserted from the inner side of the partial denture and is therefore concealed from view.

Another object is to provide a dental stress-breaker of the type indicated in which there exists minimum clearance between its relatively

movable components so that the presence of crevices or cavities, in which particles of food may lodge, is avoided. A related object is to provide such a stress-breaker which, due to the 5 closely fitting slide and support bar members, prevents transverse rocking of the partial denture.

A further important object is to provide a dental stress-breaker which is self-adjusting so 10 as to allow the partial denture to normally rest lightly against the gum tissue to provide a comfortable fit, this feature enabling the partial denture to adjust itself to the contour of the gum tissue to compensate for shrinkage of the tissue.

A still further object is to provide a dental stress-breaker which is composed of a minimum number of parts each adapted for economical manufacture from precious alloys. A related object 20 is to provide a device of this character, the major parts of which may be made from plastic to serve as male patterns for forming cavities or matrices in which the parts may be cast from selected alloys.

Further objects of the invention will appear 25 from the following description, and from the drawing, which is intended for the purpose of illustration only, and in which:

Fig. 1 is a perspective view of a pair of our 30 improved dental stress-breaker devices, showing them applied to use in connecting a pair of partial dentures to abutment teeth of the lower jaw of a person;

Fig. 2 is an enlarged plan view of one of the 35 partial dentures and one of the improved stress-breaker devices, as applied to the left-hand side of the lower jaw;

Fig. 3 is a side elevational view of the same, 40 as viewed in the direction of the arrow 3 in Fig. 2, the partial denture being illustrated in its normal position, prior to a mastication process;

Fig. 4 is a view similar to Fig. 3, with certain 45 components shown in section, the partial denture being illustrated in the depressed position assumed thereby during the mastication process; and

Fig. 5 is a cross-sectional view, taken on line 5-5 of Fig. 3.

Referring to the drawing in detail, our improved dental stress-breaker devices 10 are shown 50 as applied to use in connecting a pair of partial dental restorations or dentures 11 to natural abutment teeth 12 at the opposite sides of the lower jaw 13 of a person. Since the stress-breaker devices are alike, except that they are of opposite hand, only the device 10 employed at the left-hand side of the jaw will be described at this point.

The partial denture 11 used at the left-hand 60 side of the jaw 13 may be more or less conventional in structure, and may consist of a saddle 15 of inverted channel shape made from any suitable material, such as a moldable acrylic plastic material. Artificial teeth 16 are molded into the top of the saddle 15 in the usual manner, and a retention element 17 is also embedded in the plastic material during molding of the saddle.

When the partial restoration includes a pair 70 of the partial dentures, as illustrated in Fig. 1, the retention elements 17 of each partial denture are connected by a curved lingual bar 18 which has its ends suitably joined to the forward or anterior ends of the elements, the bar following the contour of the dental arch or, in other words, the 75 shape of the inner surface of the gum at the lin-

gual side of the frontal teeth and in close association therewith. In prior dental work, it has been customary to provide means by which transmittal of movement of one of the partial dentures to the other partial denture is prevented, such an expedient ordinarily consisting in either making the lingual bar in two relatively movable sections, or in providing universal connecting means at the joinder of the ends of a one-piece lingual bar and the anterior ends of the denture saddles. In the former case, the relatively movable sections provide crevices in which food particles may lodge and in which the tongue may catch, and in the latter case, the universal connections weaken and break during continuous use and must be repaired or replaced quite frequently. On the other hand, by the use of our improved stress-breaker devices a one-piece lingual bar having its ends rigidly connected to the partial dentures is made possible, this feature being hereinafter explained in more detail.

Each partial denture 11 is connected to an abutment tooth 12 by means of one of the stress-breaker devices 10. Each device 10 includes a slide member 20 which is of channel shape cross section, the member having an inner side wall 21, an outer wall 22 and a posterior end wall 23. The slide member 20 may be formed integrally with the retention element 17 or may be made as a separate entity and suitably joined to the element. The walls 21, 22 and 23 define between them an open-topped channel or guideway 25, the longitudinal axis of which extends obliquely in an upward and forward direction from the retention element 17. The slide member 20 is embedded in the plastic material of the partial denture saddle 15. The upper portion of the retention element 17 provides a bottom wall 26 for the slide member 20 and this wall may have an arcuate upper surface as shown in Fig. 4.

The stress-breaker device also includes a support bar member 30 which has a rectangular cross-sectional shape of a size to adapt it to be received in the channel 25 of the slide member 20 with a snug but free sliding fit. The member 30 is formed integral with or attached to a clasp element 31 which is shaped to partially encircle the abutment tooth 12, such a clasp being conventional and being made to fit the particular case. The bar member 30 and its longitudinal axis extend obliquely downwardly and posteriorly from its point of attachment to the clasp element 31 at the same angle as the inclination of the channel 25, and the lower end of the member is rounded. At the rear of the bar member 30 is a stop face or shoulder 32 which engages a similar face or shoulder 33 on the inner surface of the wall 23 defining the rear boundary of the guideway 25. The support bar member 30 is provided with a longitudinally-extending elongate opening 34 extending in the same general direction as the longitudinal axes of the guideway 25 and the bar member 30. At the top of the support bar member 30 is a head 34a overlying the top of the guideway 25 in closing relationship, the bar member 30 depending from this head to leave flanges shaped to conform to and normally in contact with the terminal edges of the walls 21, 22 and 23, as suggested in Figs. 3 and 5, to limit the movement of the denture in a direction toward the opposite jaw. A shelf 34b of the head 34a may overlie a portion of the abutment tooth 12.

The bar member 30 may be retained within the slide member 20 by various connecting means and we have found that the screw 35 shown in

Fig. 4 is especially suitable for the purpose, although it is within the concept of the invention to employ a pin or other means, if desired. The screw 35 has a shank portion 36 which passes through a hole in the inner side wall 21 of the slide member and through the elongate opening 34 of the support bar member, the screw having a tapered head 31 adapted to seat in a countersunk portion of the hole of the side wall 21. The end 38 of the screw 35 is reduced in diameter and is threaded to adapt it to be screwed into a threaded aperture in the outer side wall 22 of the slide member. It is thus seen that the connecting screw 35 is inserted from the inner or lingual side of the partial denture and this is concealed from view from the exterior of the mouth. If, for any reason it is desired to disassemble the stress-breaker device, this may be readily accomplished by merely removing the screw 35.

Assuming that the stress-breaker devices 10 are in place in the mouth, as shown in Fig. 1, and that food is being masticated by the teeth at the left-hand side of the mouth, as pressure is applied against the left-hand partial denture 11, the latter is depressed and this is made possible by the compressibility of the soft gum tissue therebeneath. As the partial denture 11 is thus forced downwardly, the slide member 20 carried thereby is also depressed. Due to the inclination of the elongate opening 34 in the fixed support bar member 30, the connecting screw 35 is caused to move downwardly and posteriorly therein so that a similar movement is imparted to the partial denture 11. It is to be noted at this point that the length of the elongate opening 34 is such that the permissible downward movement of the partial denture is very slight, being on the order of approximately .040 inch, and that the rearward component of movement is a small per cent of said downward movement. During the depression of the partial plate 11, the shoulder 33 of the slide member 20 may engage the shoulder 32 of the support bar member 30 to limit the downward movement of the partial denture with respect to the abutment tooth 12.

Due to the downward movement of the partial denture 11, relative to the support bar member 30, a bending moment of the partial denture about the abutment tooth 12, which would occur if the forward end of the denture was secured fast thereto, is entirely avoided so that the abutment tooth is not subjected to a stress which might tend to loosen the same from its socket in the jaw. It is to be particularly noted that by the improved construction of the stress-breaker device pivotal movement of the partial denture is possible at all times and this has the advantage of allowing either end of the denture to depress to a greater extent than the other end thereof, depending upon which end is subjected to greater pressure during the mastication process and upon the degree of shrinking of the gum tissue beneath the denture. By trimming the shoulder 33 and extending the elongate opening 34, the extent of movement of the partial denture can be increased to meet the requirements.

Due to the rearward or posterior component of movement of the partial denture 11 during the depression thereof, pressure of the anterior end of the partial denture 11 against the abutment tooth 12 or against the gum tissue adjacent the same is relieved so that any tendency to loosen the abutment tooth is avoided. Of equal importance is the fact that during the depression of the partial denture and the slight posterior move-

ment thereof, the lingual bar 18 is drawn rearwardly so that pressure thereof against the gum tissue at the rear of the frontal teeth is relieved. By this provision, abrasion of the gum tissue by either frontal pressure or vertical sliding movement of the lingual bar thereagainst is wholly avoided and maximum comfort for the wearer is assured. When the mastication process is effected only by one partial denture, only that end of the lingual bar which is connected to that particular denture may be drawn rearwardly but when both partial dentures are active, the entire lingual bar is displaced in the posterior direction.

Thus far, our improved stress-breaker device has been described as adapted for use in connection with a partial denture applied to an abutment tooth of the lower jaw. The device is, however, equally adaptable for use in connection with partial dentures applied to an upper jaw. In such case, the elongate opening 34 extends upwardly and posteriorly with respect to the abutment tooth so that during mastication of food the partial denture is forced upwardly and rearwardly while being free to pivot slightly, so as to avoid strain on the abutment tooth and prevent pressure of the partial denture thereagainst.

It will be observed from the foregoing that our improved stress-breaker device is simple in construction and highly efficient in performing its intended function. As pointed out in considerable detail, the device is so constructed and connected between the partial denture and an anterior abutment tooth that the denture is caused to move obliquely in a direction away from the horizontal plane of the teeth of the jaw and posteriorly of the abutment tooth. By this means, the abutment tooth is relieved of all stresses which are ordinarily transmitted thereto by movement of the partial denture when the latter is rigidly connected to the abutment tooth or joined thereto by stress-breaker devices heretofore employed. As an important consideration, posterior movement of the partial denture relieves pressure of the lingual bar against the gum tissue and this adds greatly to the comfort of the wearer by avoiding an abrasive action. In addition, by the use of our improved stress-breaker device, the partial denture may pivot slightly so that the denture is in effect, self adjusting to the contour of the gum. This action, together with the oblique movement of the partial denture permits the same to move toward and away from the jaw to compensate for shrinking or swelling of the gum tissue and thus provide a comfortable fit at all times.

It will be apparent to one skilled in the art that various modifications might be made in the construction without departing from the spirit of the invention. Consequently, we do not wish to be limited in this respect but desire to be afforded the full scope of the appended claims.

We claim as our invention:

1. A dental connection for use in connecting a partial dental plate to a natural abutment tooth of a jaw at the posterior side thereof, comprising: a slide member secured to the partial plate at the anterior end thereof, said member being of channel shape and defining a guideway having side walls and a posterior wall, said guideway being inclined with respect to the vertical and sloping obliquely from the horizontal plane of the teeth of the jaw and in a posterior direction from said anterior end of said plate; a support bar member adapted to be detachably connected to

the abutment tooth, said bar member being disposed in said guideway and having a longitudinal sliding fit therein, one of said members having an elongate opening also sloping obliquely from said horizontal plane of the teeth in a posterior direction; and a connector element carried by the other of said members and extending transversely through said elongate opening of said one member so as to allow up and down but obliquely-guided movement of said partial plate relative to said bar member in a path extending obliquely away from the horizontal plane of the teeth of the jaw and posteriorly with respect to the axis of the abutment tooth.

2. A stress-breaker for use in connection with a natural abutment tooth and a partial plate mounted posteriorly of said abutment tooth, comprising: a slide member carried by said plate at the anterior end thereof; a support bar member adapted to be detachably connected at its anterior side to said abutment tooth; and interengaging means on said bar member and said slide member connecting said members and sloping posteriorly toward the jaw to provide a sliding movement of said slide member with respect to said bar member in a path extending obliquely away from the horizontal plane of the teeth of the jaw and in a posterior direction to move said partial plate posteriorly away from said abutment tooth as said partial plate is depressed toward the jaw by mastication pressure.

3. A dental stress-breaker for use in connecting a gum-engaging tooth-holding denture to a natural abutment tooth in a space adjacent such abutment tooth, said stress-breaker comprising: a first member secured to said denture; a second member adapted to be secured to said abutment tooth, one of said members comprising a slide member having an open-topped guideway having a central plane substantially parallel to the axis of said abutment tooth and substantially in the line of said teeth, the other of said members comprising a support bar longitudinally slidable in said guideway and having an elongate opening sloping posteriorly away from said axis of said abutment tooth in a direction toward the gum; and a connector element carried by said one of said members and extending substantially transversely of said central plane and through said elongate opening, said elongate opening and said connector element guiding said denture to move posteriorly away from the abutment tooth as mastication pressure depresses said denture relative to the gum it engages.

4. A dental stress-breaker for use in connecting a gum-engaging tooth-holding denture to a natural abutment tooth in a space adjacent such abutment tooth, said stress-breaker comprising: a slide member carried by said denture at the anterior end thereof, said slide member defining an open-topped guideway having a central plane substantially in the plane of the axes of said abutment tooth and the tooth of said denture; a support element adapted for connection to said abutment tooth and providing a bar member extending slidably in said guideway through the open top thereof, one of said members providing a wall-bounded elongate opening sloping posteriorly toward the gum and relative to the axis of said abutment tooth; and a connector element carried by the other of said members and extending through said elongate opening, said connector element engaging the walls of said elongate opening to guide said denture to move posteriorly away from the abut-

ment tooth as gum-compressing pressure is applied to said denture and because of said posterior slope of said elongate opening.

5. A dental stress-breaker as defined in claim 4 in which said support element provides a head extending across the open end of said guideway in closing relationship therewith.

6. A dental stress-breaker as defined in claim 4 in which said slide member provides walls bounding said guideway on at least three sides, said walls having edges facing away from the gum which carries said abutment tooth, and in which said support element provides a head having flanges extending beyond the periphery of said bar member to overlie said edges of said walls.

7. A dental stress-breaker as defined in claim 6 in which said flanges provide lower surfaces engageable with said edges of said walls to limit the movement of said denture relative to said abutment tooth in one direction.

8. A dental stress-breaker for use in connecting a gum-engaging tooth-holding denture to a natural abutment tooth in a space adjacent said abutment tooth, said stress-breaker comprising: a slide member carried by said denture at the anterior end thereof, said slide member having a guideway open anteriorly on the posterior of said abutment tooth and providing an open top, the sides of said guideway being closed by side walls and the posterior of said guideway being closed by a posterior wall extending between said side walls; a support element adapted for connection to said abutment tooth and providing a head extending across said open top of said guideway and a bar member depending through said open top and shaped to slide up and down relative to said guideway; and means for pivotally connecting said bar member and said slide member at a position within said guideway to swing about an axis substantially perpendicular to a plane joining said abutment tooth and the adjacent tooth of said denture, said means including means providing a limited up and down movement of said slide member relative to said bar member and means for limiting the pivoting of said slide member relative to said bar member to limit the movement of said denture away from the gum.

9. A dental stress-breaker for use in connecting a gum-engaging tooth-holding denture to a natural abutment tooth in a space adjacent said abutment tooth, said stress-breaker comprising: a slide member carried by said denture at the anterior end thereof, said slide member having a guideway open anteriorly on the posterior of said abutment tooth and providing an open top, the sides of said guideway being closed by side walls and the posterior of said guideway being closed by a posterior wall extending between said side walls; a support element adapted for connection to said abutment tooth and providing a head extending across said open top of said guideway and a bar member depending through said open top and shaped to slide up and down relative to said guideway; and means for pivotally connecting said bar member and said slide member at a position within said guideway, said means including means providing a limited up and down movement of said slide member relative to said bar member and means for limiting the pivoting of said slide member relative to said bar member to limit the movement of said denture away from the gum, said last named means including a stop shoulder on said posterior wall

facing anteriorly and engageable with a posterior edge of said bar member.

10. A stress-breaker as defined in claim 9 in which said posterior wall provides a guideway-bounding surface facing anteriorly and traversing a plane joining the axes of said abutment tooth and the tooth of said denture, said bar member lying substantially in said plane, said guideway-bounding surface extending in a direction toward the gum and which direction diverges posteriorly from the axis of said abutment tooth, said bar member providing a posterior edge engaging said surface, said means for providing a limited up and down movement of said slide member relative to said bar member including means for limiting such relative movement to said direction diverging posteriorly from the axis of the abutment tooth.

11. A stress-breaker as defined in claim 8 in which said means for pivotally connecting said bar member and said slide member and for providing said limited up and down movement thereof includes an elongate opening in said bar member extending in a direction toward the gum which diverges posteriorly from the axis of said abutment tooth, and a removable connector element extending through at least one of said side walls and through said elongate opening.

12. A dental stress-breaker for use in connecting a gum-engaging tooth-holding denture to a natural abutment tooth in a space adjacent such abutment tooth, said stress-breaker comprising: a first member adapted to be secured to said denture; and a second member adapted to be secured to said abutment tooth, one of said members comprising a slide member having an open-topped guideway bounded on at least three sides by walls including side walls and an end wall connecting such side walls, said guideway sloping toward the gum in a direction away from the axis of the abutment tooth, the other of said members comprising a bar longitudinally slid able relative to said guideway, said members providing engaging surfaces guiding the relative movement of said bar and said guideway so that this relative movement is in said direction sloping toward the gum and away from the axis of said abutment tooth to displace said denture away from the abutment tooth as mastication pressure depresses said denture relative to the gum it engages, said end wall comprising one of said engaging surfaces.

13. A dental stress-breaker as defined in claim 12 in which said engaging surfaces comprise also the bounding walls of an opening and the peripheral wall of a pin extending into said opening, said opening and said pin being respectively parts of said members, said opening being elongated in said direction away from the axis of said abutment tooth.
